UNITED STATES PATENT OFFICE.

AARON P. GOULD, OF CANTON, OHIO.

SURGICAL CHAIR.

SPECIFICATION forming part of Letters Patent No. 453,184, dated June 2, 1891.

Application filed June 22, 1887. Serial No. 242,132. (No model.)

To all whom it may concern:

Be it known that I, AARON P. GOULD, a citizen of the United States, and a resident of Canton, county of Stark, State of Ohio, have 5 invented a new and useful Improvement in Surgical Chairs, of which the following is a full, clear, and exact description, reference being had to the accompanying drawings, making part of this specification.

10 My invention relates to improvements in surgical chairs, the object of which is to provide a chair that may be made to assume the various positions required for examination and treatment in surgical operations; and it 15 consists of the parts and combinations of parts hereinafter described, and set forth in the claims.

Figure 1 is a view of the chair in horizontal adjustment. Fig. 2 is a view in which the 20 back is shown in horizontal position, the seat and leg-rest being dropped down to their normal position. Fig. 3 shows the back in horizontal adjustment, with the seat inclined, and the leg-rest in normal position. Fig. 4 shows the 25 back, seat, and leg-rest adjusted to the same inclination, with the head-rest lower than the foot-rest. Fig. 5 shows the back in horizontal adjustment, the seat raised and inclined, and the leg-rest dropped to normal position. Fig. 30 6 shows the parts in normal position, the chair tipped diagonally forward to disclose the details. Fig. 7 is a view in perspective of the rotary chair-body support and locking-frame. Fig. 8 is a view in perspective of a 35 swinging locking frame or latch. Figs. 9 and 10 are detached views of the seat-frame and operating mechanism. Fig. 11 is a detail view of the base of the chair, showing the stem of the body-support having a screw-threaded 40 connection with the tubular body portion of the said base. Figs. 12 and 13 represent enlarged detail views of parts.

The purpose of the positions shown by the figures of the accompanying drawings are 45 well known to the profession and will require no explanation in a detailed description of the construction of the chair. That I attain the object set forth effectually and expeditiously is fully shown and described.

50 Letter A represents the base of the chair, which is preferably made of cast metal, the upper portion, in the form of a tubular body a,

from which the legs a' are projected downwardly and outwardly, forming a broad base-support. The revolving body-support B has a 55 lower or stem portion a², cylindrical in form and adapted to rotate in the tubular body portion of the base A, as shown in Figs. 6 and 7. If preferred, the tube in the body portion and the stem portion of the body-support may 60 be provided with annular screw-threads adapted one to the other, as shown in Fig. 11, for the purpose of adjusting the body of the chair to any height. In the form shown in Figs. 6 and 7 the shoulder a³ of the body-support rests on the flange a⁴ of the body portion of the base. For the purpose of arresting the rotary movement of the body-support, the clamping-screw a⁵, turned into a threaded boss a⁶ on the side of the tubular body portion of the base, may be turned in against the stem of the body-support, by which the base and the body-support may be held in a rigid adjustment. 70

From the upper end of the stem a² of the rotary body-support B arms a⁷ are projected outwardly and upwardly, at the upper end of which there is formed a pivotal connection a⁸ with the body-frame C of the chair, about which it may be rocked or vibrated. To fix the body of 75 the chair at any desired inclination or position within the limits of vibration about the said pivotal connection a⁸, there is projected from the rotary body-support B a segmental rack a⁹, having perforations a¹⁰; or, if preferred, rack-teeth or notches may be used instead of the perforations herein shown. A dependent latch D is connected to and vibrates with the body of the chair about the pivotal connection a⁸, said latch having a 80 locking pin or tooth b, adapted to the perforations a¹⁰. For convenience in operating said latch a foot-piece b' is provided and a spring b², the said spring holding the latch in engagement with the rack, and by pressing the 85 foot on the plate b' the latch may be disengaged and the tooth withdrawn from the rack and the chair-body vibrated over the base and again locked in the desired adjustment. 90

The back-section E is supported between 100 the arm-supports F on pivots or trunnions b³, located near the upper rear portion, about which the said back-section may be vibrated from a horizontal to a vertical position and

held in adjustment by turning the set-screw b^4 against the curved arm b^5 , said arm having at its upper end a pivotal connection with the back-section, as b^6 , while the free end of 5 said curved arm is passed through the loop b^7 .

An auxiliary rocking frame by which the seat may be raised and lowered and by which the back-section E and the seat-section G have a pivotal connection, and which also is 10 a means of locking the back and seat in adjustment, is provided, and consists of an open V-shaped portion H and two arms d, extending from the V-shaped portion parallel to each other and pivotally secured to the sides of 15 the back-section near their lower ends and to the sides of the seat-section near their rear ends by suitable bolts or studs d' d², which extend through perforations in the arms d. The V-shaped portion of the frame, when in 20 position, is located beneath the seat-section and pointing toward the front and downwardly.

The rock-shaft J is pivoted to lugs d⁴, projected from the seat-frame K, by means of the 25 arms d⁵, integral with the shaft, the outer end of the shaft terminating in an operating-crank d⁶.

On the under side of and rigidly connected with the seat-frame K there is provided a 30 cross-bar L, a spring-actuated catch R, formed of a rod d⁷, sliding in perforations in the depending lugs d⁸, secured to or integral with said bar. The inner end of said rod has a depending catch-hook d⁹, adapted to take under 35 the arm f, which is a prolongation of the arm d⁵ on the inner end of the shaft J when the said arm f is elevated for adjustment. The arm f extends through a slot f' at the vertex of the V-shaped portion of the rocking 40 frame and has a sliding movement therein. A spiral spring f² is secured on the rod d⁷, between the lug d⁸ and a shoulder f³, and by its tension holds the catch d⁹ in locking adjustment. The front of the seat-section G is pivotally attached to the front inner face of the 45 arm-support F' in a swinging adjustment by means of a pair of depending arms b⁸, loosely secured at the upper end on inwardly-projected studs or bolts f⁴ on the inner face of the 50 arm-support F', and on studs or bolts f⁵, set in the side of the seat-section near their front ends. The pivotal bolts f⁵ on each side are also connected with bolts f⁸ on the inner face of the arm-support F', below the bolts f⁴, by a 55 jointed arm consisting of sections f⁶ and f⁷. The leg and foot rest section N is hinged to the seat-section G by means of corner extensions h, formed with elongated slots h', which 60 embrace the pivotal bolts f⁵. The extensions h, after passing the bolts f⁵, are bent at right angles and extend rearward a short distance, terminating in open hooks h², adapted to receive short studs h³ on the inner sides of the jointed arm-section f⁶. The slots h' are sufficiently elongated to admit of the extension h slipping outwardly and upwardly enough to 65 free the hooks h² from the studs h³ and allow

the foot and leg rest section to depend in a free swinging motion from the bolts f⁵; but when the hooks h² are engaged with the studs h³ the foot and leg rest section will be subject to such changes as are determined by the combined action of the arms b⁸ and the jointed arms f⁶ f⁷.

For the purpose of holding the feet of the 75 patient in a suitable position for certain classes of operations, stirrups P are provided, the stems n of which are secured in longitudinal adjustment in the rotary adjustable clamps o³⁰, provided with a tail-nut o⁵, for the 80 purpose of clamping the stem n of the stirrup in any desired longitudinal adjustment, and also for the purpose of locking at the same time the clamp in any desired rotary adjustment. By the above construction the stirrups 85 may be adjusted and locked in any desired vertical or angular adjustment.

A chair constructed as hereinbefore described may be operated as follows: Presuming the chair to be in normal position, as 90 shown in Fig. 6. If now the curved arm b⁵ be released and the back-section pressed backward and down, pivoting as a lever over the trunnions b³, the seat and leg rest sections may be raised to a horizontal plane with the 95 back-section, the lower end of the back being pivoted to the arm d of the rocking frame H, by which the seat is moved forward and up. This motion of the seat-section will also, by the combined action of the arms b⁸, f⁶, and f⁷ and 100 the bent extensions h, with their hooked ends h² in engagement with the studs h³ on arm f⁶, gradually elevate the leg-rest section, in which position the parts may be secured by turning the screw b⁴ against the curved arm b⁵. The 105 patient being now on the chair for certain operations, the feet may be secured in the stirrups P. If now the spring-catch R d⁹ be released from engagement with the rocking 110 frame and the crank d⁶ turned to a vertical 110 position, the seat and leg sections may be dropped away from the person to position as shown in Fig. 2, and when the chair is so occupied, for the purpose of better illuminating 115 the subject, the body of the chair may be rotated on the base A, the stem a² of the body-support B turning in the tubular portion of the base A, and may be fixed in adjustment by the handle-screw a⁵, and, if required, the lower portion of the patient's body may be 120 raised by disengaging the latch D from the rack a⁹ and rocking the body of the chair back over the pivot a⁸ of the body-support B; or, if required, when the body of the chair is 125 so rocked or tipped back the seat-section may be raised up, as shown in Fig. 5, to support the patient, the back-section raised to a horizontal position, the hooks h² released from the studs h³ will allow the leg and foot rest to 130 depend in a swinging position over the bolts f⁵; or with the parts in position as shown in Fig. 1, by releasing the latch D from rack a⁹ the position may be changed to that shown in Fig. 4, by which the head of the patient

may be placed below the feet; or when back, seat, and leg rest sections are in normal position, as shown in Fig. 6, by releasing the locking-latch D the body of the chair may be rotated or rocked vertically about the horizontal body-supporting pivots a^8 and fixed in adjustment by the latch D, engaging the rack a^9 , and the chair, when in any of the positions that it may be made to assume, may be rotated horizontally about a vertically-supporting pivot.

Having thus fully described the nature and object of my invention, what I claim, and desire to secure by Letters Patent, is—

- 15 1. In combination, a tilting back-section, a seat-section having a swinging movement independent of its tilting support, a swinging leg-rest section, connections between the back, seat, and leg-rest sections which communicate the movements of the back-section to the seat and leg-rest sections, and a support common to the several sections and having a tilting movement backward of a vertical line, substantially as set forth.
- 20 2. In combination, a tilting back-section, a seat-section having a swinging movement independent of its tilting support, a swinging leg-rest section, connections between the back, seat, and leg-rest sections which communicate the movements of the back-section to the seat and leg-rest sections to throw the several sections into substantially a horizontal plane, and a support common to the several sections and having a horizontally-rotary adjustment
- 25 3. In combination, a tilting back-section, a seat-section having a swinging movement independent of its tilting support, a swinging leg-rest section, connections between the back, seat, and leg-rest sections which communicate the movements of the back-section to the seat and leg-rest sections, a swinging frame for adjusting the seat-section, a swinging-frame-actuating device independent of the back-section, and a support common to the several sections and having a horizontally-rotary adjustment and a forwardly 40 and backwardly tilting adjustment, substantially as set forth.
- 30 4. In combination, a tilting back-section, a seat-section having a swinging movement independent of its tilting support, a connection between the back and seat sections through which the back-section controls the movements of the seat-section, and a support common to the two sections and having a tilting adjustment backward of a vertical line, substantially as set forth.
- 35 5. In combination, a tilting back-section, swinging seat and leg-rest sections controlled in their movements by the back-section, and a support common to the several sections and having a horizontally-rotary adjustment, a forwardly and backwardly tilting adjustment, and a vertical adjustment, substantially as set forth.

In testimony whereof I have hereunto set my hand this 18th day of June, A. D. 1887.

AARON P. GOULD.
